UNITED STATES PATENT OFFICE.

WALTER GORDON LAWRENCE, OF WINTON, ENGLAND.

WINDOW.

1,109,769.

Specification of Letters Patent.

Patented Sept. 8, 1914.

Application filed September 12, 1912. Serial No. 719,984.

To all whom it may concern:

Be it known that I, WALTER GORDON LAWRENCE, a subject of the King of Great Britain, and a resident of 214 Worsley road, 5 Winton, in the county of Lancaster, England, have invented certain new and useful Improvements in Windows; and I do hereby declare that the following is a full, clear, and exact description of the same.

10 The invention relates to improvements in windows, as described in the present specification and illustrated in the accompanying drawings that form part of the same.

15 The invention consists essentially in the novel form of self adjusting hinge support for casement windows.

20 The objects of the invention are to be able to get at all parts of the window for cleaning purposes no matter which way the sash is swung, to devise a simple and efficient means of supporting the sashes in casement windows which will avoid all clogging and jamming of the sash at the hinged portion as the frame can readily be cleared of all 25 obstruction, and generally to provide a simple, cheap and durable window.

25 In the drawings Figure 1 is a perspective view of the pivotal support or hinged member at the lower end of the sash showing the other hinge member attached to the frame. Fig. 2 is a plan view of the arrangement shown in Fig. 1 with a partly open position of the sash indicated by dotted lines. Fig. 3 is an enlarged sectional detail of a hinge pin 30 and slotted plate. Fig. 4 is a sectional view of another hinge pin and the slotted plate.

35 Like numerals of reference indicate corresponding parts in each figure.

40 Referring to the drawings 1 is a vertical rail of the window sash.

2 is a horizontal sash rail.

3 is a window frame formed of metal or wood as desired, though in the accompanying drawings a metal frame is shown, also 45 a metal sash.

4 is a hinge member rigidly secured to the horizontals of the frame 3 and having a plate surface 5 parallel with the said horizontals and a parallel slot 6 extending the greater part of its length and a lug 7 extending outwardly from one end of said plate portion 5 in an oblique direction and formed in opposing curves 8 and 9 with a recessed interior flanged at the sides by the flanges 10 and 11, forming the under cuts 13. The under cuts 13 are formed by a cut into

the longitudinal under corners of the lug 7, said lug having in the bed of the recess the holes 14 with the bevel edges 15.

16 is a bracket formed with the boss 17, 60 the plate extensions 18 and the pin 19 extending from said boss into the slot 6, said plate extensions 18 being rigidly secured to the vertical rail 1 and the horizontal rail 2 at the corner thereof.

65 20 is a bracket flanged at its inner end 21 and rigidly secured to the horizontal rail 2 adjacent to a plate extension 18, said bracket 20 extending outwardly and carrying at the outer end thereof the pin casing 22, said pin 70 casing having a shoulder 23 in the interior thereof and at its lower end a flange 24 extending into the under cuts 13.

75 25 is a pin having at its lower end the round head 26 and extending upwardly into 70 and through said pin casing 22.

80 27 is a spiral spring encircling the pin 25 between the flat inner side of the round head 26 and the shoulder 23, thereby constantly exerting a downward pressure on the head 80 26 so that the said head will engage in one or other of the holes 14. The hinge members 4 and 20 are secured in pairs to the corners of the window frame and to the sash as usual.

85 In operating the window which is of the casement style opening outwardly, when the sash is pushed outwardly, the pin and pin casing carried at the end of the bracket 20 are first moved outwardly in the recess 10 90 following the first curve 8 and as soon as the opposing curve is reached the pin 19 begins to move along in the slot 6, the pin casing 22 in the meantime moving toward the outer end of the recess 10, but as the window is 95 moved to a perfectly right angular position in relation to the frame, the said pin casing and pin move back a little. The several holes 14 by the engagement of the spring pin 25 therein, hold the sash in the various positions according to how much it is desired to open said sash.

100 It will be now seen from the description of the details of this invention that it is of a very simple character and answers a very useful purpose for there could never be any jamming from ice, snow or other causes between the sash and the frame for said parts are so constantly cleared from one another also cleaning of the window panes is very 110 much facilitated because it is just as easy to rub one side as the other, especially when

it gets in a right angular position, without any necessity of being on the outside.

What I claim is:

A window frame, a window sash, a bracket 5 secured to said window frame at the lower end and having a longitudinal slot parallel with the lower horizontal of said frame and a lug extending outwardly from the inner end toward the outer end, said end being 10 formed in opposing curves and channeled to form a slideway and having beveled recesses at intervals in said channel, a bracket secured to said sash and having a boss and a

pin projecting downwardly from said boss into said longitudinal slot, an arm secured 15 to said sash and carrying at the extremity thereof a pin casing and a pin spring held to its lower position in said casing and engaging said lug in said channel and recesses.

Signed at Jamestown, N. Y., this fifteenth 20 day of August, 1912.

WALTER GORDON LAWRENCE.
